UNITED STATES PATENT OFFICE.

JOSEPH F. WINKLER, OF PHILADELPHIA, PENNSYLVANIA.

REFRIGERATING APPARATUS.

1,206,633.

Specification of Letters Patent. Patented Nov. 28, 1916.

Application filed December 4, 1915. Serial No. 65,127.

To all whom it may concern:

Be it known that I, JOSEPH F. WINKLER, a citizen of the United States, residing in Philadelphia, Pennsylvania, have invented 5 the Refrigerating Apparatus of which the following is a specification.

This invention relates particularly to refrigerating machines of the compression type designed for house-hold use, one object 10 being to so arrange and design the parts that the liquefied refrigerating medium will automatically pass from the condenser to the evaporating chamber, while said medium in gaseous form is prevented from so 15 passing, being retained in said condenser.

I further desire to provide a refrigerating machine in which the parts shall be so designed and arranged as to insure the proper lubrication of the moving elements, the arrangement being such that the lubricant is 20 used at a low temperature.

Another object of the invention is to provide a simple, efficient and inexpensive form of domestic refrigerating machine which 25 shall be capable of operating practically without attention and with a minimum liability of getting out of order.

I also desire that the machine constructed in accordance with this invention shall include 30 means for freezing liquid contained in cans, said invention contemplating a novel combination of evaporating chamber, brine tank and liquid containers for accomplishing this end.

These objects and other advantageous ends 35 I secure as hereinafter set forth, reference being had to the accompanying drawings, in which,

Figures 1 and 2 are respectively a side 40 elevation and a plan of a refrigerating machine constructed according to my invention; Figs. 3 and 4 are vertical sections taken respectively on the lines *a—a*, and *b—b*, Fig. 2; and Fig. 5 is a horizontal section 45 on the line *c—c*, Fig. 3.

In the above drawings, 1 represents an 50 elongated container made of metal of sufficient structural strength to withstand the pressures existing under all conditions of 55 operation. The lower portion 2 of this container constitutes an evaporating chamber and is of elongated cylindrical form having longitudinally extending or otherwise suitably disposed radiating vanes or fins 3 projecting from its external surface. While the lower end of this container is perma-

nently closed, its otherwise open upper end is provided with a removable cover 4 and it likewise has a side opening closed by a removable bearing structure 5. Extending 60 across the upper portion of the container 1 is a partition 6 dividing it into two chambers of which the lower 2, as before indicated, constitutes the evaporating compartment while the upper 7 constitutes or forms 65 part of a condenser.

The partition 6 is so designed as to provide at one side, preferably opposite the bearing 5, a well 8 having within it an open top casing 9 for the reception of an elongated float 10. The lower part of the casing 70 is attached to a short bushing 11 having in its upper part a valve seat 12 designed to coöperate with a needle valve 13 carried by the lower end of the float 10, the arrangement being such that as said valve rises 75 under the action of a body of liquid within the casing 9, the valve moves away from said seat and permits passage of liquid into the evaporating chamber, although when the 80 level of said liquid has fallen a predetermined distance, the float, which is guided in its movements by the casing 9, moves the valve into engagement with the seat to cut off further flow of liquid.

Preferably, though not necessarily, formed 85 integral with the partition structure 6 is a central vertical extending pump cylinder 14 open at both ends although its upper end is normally closed by a valve 15 held seated 90 on the upper edge of the cylinder structure by a spring 16. This latter is operative in a cavity formed in the cover 4 and true vertical movement of the valve is insured by its provision with a stem 17 which slides in 95 said cavity and is hollowed for the reception of said spring. The cylinder 14 has operative within it a tubular plunger 18 whose lower end is laterally extended to provide a head 19 having a laterally extending 100 rectangular opening or slot for the reception of a rectangular block 20 slidably movable therein. This block is held in place on one side by the adjacent vertical face of the partition 6 and on the opposite side by 105 a crank 21 whose pin 22 extends through the block. Said crank is mounted on a driving shaft 23 journaled in the bearing structure 5 and having outside of the container 1 a pulley 24 driven from any suitable source 110 of power. It is noted that the bearing structure 5 has extending into it a cavity through

which the shaft passes and containing packing 25 held in place by a gland 26, so that escape of refrigerating medium along said shaft is effectually prevented. That portion 5 of the bearing structure 5 which extends into the evaporating chamber 2 toward the crank 21, has a cup-shaped hollow 27 formed in its upper portion and there are passages 28 leading from this hollow to the journal in 10 which the shaft 23 rotates.

The plunger 18 has a passage 30 extending longitudinally through it and opening into the rectangular slot 21 in the head 19 so that the block 20 cannot close the entrance 15 to the slot. The upper end of the passage 30 is formed with a seat for the reception of a valve 32 including an elongated stem guided in said passage and designed to have a limited vertical movement controlled by a 20 pin 33, which is operative in slots in said stem, there being passages opening below the valve from the interior of the stem.

For the purpose of supplying lubricant to the various moving parts, the plunger 18 is 25 provided with a downward extension 34 constituting an auxiliary plunger designed to operate in a cylinder 35 formed as part of a casing 36 bolted or otherwise fixed within the evaporating chamber 2. The lower end 30 of this latter cylinder has connected to it an inlet or suction conduit 37 extending to within a short distance of the bottom of the evaporating chamber and there is also provided a check valve 38 whereby liquid entering 35 the cylinder from said conduit is prevented from returning through the latter. The casing 36 also has a passage 39 leading from the cylinder to a conduit 40 so placed as to discharge to a greater or less extent 40 into the cup-shaped recess 27 and also on to the crank 21 and the lower end of the plunger 18. This passage 39 has a check valve 41 placed adjacent the cylinder 35.

The upper part of the container 1 immediately below the driving shaft 23 is preferably formed with a laterally extending flange 42, from which depends a relatively thin metal casing 43 extending around the lower portion of the evaporating chamber 2. 45 As shown in Fig. 5, both flange and casing are extended at one side of the evaporating chamber to provide a space for the reception of elongated cans 44 having flanges at their upper ends. These cans project through 50 openings in the flange 42 and are suspended by their flanges 45 within the space inclosed by the casing 43, which under conditions of operation is filled with brine.

In the annular space above the partition 60 6 and surrounding the cylinder 14, I mount a suitable length of pipe 46 in the form of a coil, whose ends 47 and 48 extend through the top of the cover 4 to which they are welded, soldered or otherwise so connected 65 as to form an absolutely tight and prefer-

ably permanent joint. Said ends are connected respectively to a source of cold water supply and to a waste pipe or receptacle for the water used for condensation.

In using my apparatus, a quantity of suitable lubricant such as oil, is placed within the evaporating chamber 2, where it occupies the position indicated at x . There is also delivered to said chamber a quantity of liquefied ammonia or other refrigerating medium x' , while as above noted, the casing 43 is filled with brine. Since the upper part of the evaporating chamber is connected to the slot 31 and passage 30 in the plunger 18, the operation of said plunger by the shaft 23 and pulley wheel 24 continuously reduces the pressure in said chamber 2, causing the liquid x' to evaporate. As a result, the brine in the container 43 is cooled by reason of the absorption of its heat and it not only cools the space in which the apparatus is mounted but so reduces the temperature of liquid in the cans 44 as to cause it, in the case of water, to solidify.

The gasified refrigerating medium from the upper part of the evaporating chamber 2 raises the valve 32 on each down stroke of the plunger 18 and enters the cylinder 14 from which it is forced on the succeeding upstroke past the valve 15 into the condensing chamber. As a consequence the gas is highly compressed in said chamber and is condensed by the water or other cooling medium which is circulated through the coil 46, collecting in the casing 9 within the well 10 8 and when in sufficient quantity, raising the float 10. This movement of said float opens the valve 12 and permits the liquefied refrigerant to flow in a fine stream or jet 10 into the evaporating chamber, where it either collects in the bottom or is immediately gasified with a further lowering of the temperature of the brine. Obviously it is practically impossible for any of the gas to pass from the condensing chamber to the 11 evaporating chamber, since as soon as a certain amount of liquid has flowed from the casing 9 past the valve 12 into the evaporating chamber, the float 10 falls so as to close said valve and prevent further flow of 115 liquid or any escape of gas past said valve.

The pump formed by the plunger 34 and cylinder 35 under operating conditions draws the mixture of lubricant x and refrigerant x' from the bottom of the evaporating chamber and delivers it through the conduit 40, whereby it is distributed to the cavity 27 and thence to the shaft 23 as well as to the crank and plunger. It is noted that such lubricant is at a low temperature owing to its immersion in the liquid in the evaporating chamber, so that in addition to diminishing the friction between the parts to which it is delivered, it maintains their temperature at a low point, ultimately flow- 125 130

ing down the walls of the evaporating chamber and back to the bottom thereof from whence it is repeatedly drawn through the suction pipe 37, whose lower end extends to such a depth that it is always below the surface of the lubricant. By means of mechanism forming no part of the present invention, the compressor formed by the plunger 18 and cylinder 14 is preferably 5 started and stopped automatically, depending on the temperature of the brine in the casing 43 or the temperature of the space in which said casing is mounted.

It may be noted that the apparatus above 10 described is relatively simple and compact, with the result that it is inexpensive to construct; efficient in operation and capable of running for long periods without attention.

I claim:—

20 1. The combination in a refrigerating apparatus of a container having condensing and evaporating chambers; a duct positioned to allow flow of liquid by gravity from the condensing to the evaporating chamber; a valve for said duct; and a float connected to the valve to open it when more and close it when less than a predetermined quantity of liquid is present in the condensing chamber.

30 2. The combination in a refrigerating apparatus of a casing having an evaporating chamber and a condensing chamber, of which the latter includes a well having a passage into said first chamber; a valve for said passage; with a float guided in the well and connected to open the valve only when more than a predetermined body of liquid is present.

35 3. The combination in a refrigerating apparatus of a vertically elongated container; a partition dividing said container into condensing and evaporating chambers, of which the former is above the latter; a conduit for cooling medium in the condensing chamber; and means for automatically controlling the flow of liquid by gravity from the condensing chamber to the evaporating chamber.

40 4. The combination in a refrigerating apparatus of a vertically elongated container having a partition dividing it into condensing and evaporating chambers; a cylinder carried by said partition and opening into both of said chambers; a power driven plunger for said cylinder for drawing gas 45 from the evaporating chamber and compressing it into the condensing chamber; with automatically acting means dependent for its action upon the quantity of liquid in said condensing chamber for controlling the flow of such liquid from the latter to the former chamber.

45 5. The combination in a refrigerating apparatus of a container having condensing and evaporating chambers; a cylinder opening into both of said chambers; a valve

normally closing the opening from the cylinder to the condensing chamber; a valved plunger operative in the cylinder; and a gravity controlled device for including a float operative in the condensing 70 chamber governing flow of liquid from the condensing chamber to the evaporating chamber.

6. The combination in a refrigerating apparatus of a container having condensing and evaporating chambers; a pump connected to receive gaseous refrigerant from the evaporating chamber and compress it into the condensing chamber; with a second pump connected to circulate liquid refrigerant in said evaporating chamber.

7. The combination in a refrigerating apparatus of a container having condensing and evaporating chambers; a cylinder opening into the condensing chamber; a tubular plunger operative in the cylinder and having a head provided with a slot into which the plunger passage opens; a driving crank having a block slidable in the slot; a valve controlling the flow of gas through the plunger; 90 and a second valve controlling the flow from the cylinder to the condensing chamber.

8. The combination in a refrigerating apparatus of a container having a partition dividing it into two chambers having a direct 95 connecting passage; an automatic valve controlling the flow of liquid through said passage; a cylinder carried by the partition and extending into one of the chambers; a cooling coil in the latter chamber mounted in the 100 space surrounding the cylinder; a plunger operative in the cylinder; and valves for controlling the flow of fluid to and from the cylinder and between the chambers.

9. The combination in a refrigerating apparatus of an evaporating chamber provided with an apertured flange; a brine-containing casing surrounding said chamber below the flange; and a can for material to be cooled 105 extending through the aperture of the flange into the brine in the casing.

10. The combination in a refrigerating apparatus of a vertically elongated evaporating chamber having radial vanes; a brine containing casing surrounding said chamber and projecting at one side thereof; with an elongated can or cans extending into the casing for containing liquid to be cooled.

11. The combination in a refrigerating apparatus of a condensing and an evaporating chamber; a pump for compressing refrigerant in the condensing chamber; a body of lubricant and refrigerant in the bottom of the evaporating chamber; and a second pump having its inlet extended into 115 said liquid and arranged to deliver the same to the first pump and walls of the evaporating chamber.

12. The combination in a refrigerating apparatus of a vertically elongated con-

tainer including condensing and evaporating chambers; a body of lubricant in the evaporating chamber; a pump for withdrawing gaseous refrigerant from the evaporating chamber and liquefying it in the condensing chamber; with a second pump having an inlet extended adjacent the bottom of the evaporating chamber and delivering lubricant and refrigerant to the 10 movable parts of said first pump.

13. The combination in refrigerating apparatus of a container including an evaporating chamber having a body of lubricant and refrigerant therein and a condensing chamber; a cylinder opening into both of said chambers; a second cylinder having an intake pipe extending to the bottom of the evaporating chamber; plungers respectively operative in each of said cylinders; means 15 for driving the plungers; and means for directing fluid from the second cylinder onto 20

the plunger of the first cylinder and onto the walls of the evaporating chamber.

14. The combination in refrigerating apparatus of a container having its lower portion formed to receive liquid refrigerant and a body of lubricating liquid; mechanism for compressing said refrigerant from the lower to the upper part of the container; with a pump having an inlet placed to receive the mixture of lubricant and refrigerant from the lower chamber and provided with an outlet passage to deliver such mixture to the upper part of said lower chamber. 25 30

15. The combination in refrigerating apparatus of a container having a removable cover; a pump in the container including a cylinder extending adjacent said cover; a valve carried by the cover and normally closing the outlet from the cylinder; and 35 40 means for driving the pump.

JOSEPH F. WINKLER.
